SUPPORT AND HOLDER FOR BROOMS, MOPS, AND THE LIKE

Filed March 18, 1932

Inventor:
Oliver P. Wolfe, Jr.
by Emery Booth Farney & Sonnenfeld
Attnys.

UNITED STATES PATENT OFFICE

OLIVER P. WOLFE, JR., OF BOSTON, MASSACHUSETTS

SUPPORT AND HOLDER FOR BROOMS, MOPS, AND THE LIKE

Application filed March 18, 1932. Serial No. 599,766.

My invention relates to article supports, particularly useful in connection with such articles as brooms, mops, shovels, and other articles having elongated handles.

5 The invention will be best understood from the following description when read in the light of the accompanying drawing of one embodiment of the invention, the scope of which latter will be more particularly 10 pointed out in the appended claims.

In the drawing:

Fig. 1 is a plan of an article holder constructed according to the invention;

15 Fig. 2 is a side elevation of the article holder according to Fig. 1;

Fig. 3 shows a support for a broom or the like, which support includes the article holder illustrated by Figs. 1 and 2; and

20 Fig. 4 is a section on the line 4—4 of Fig. 3, with parts omitted.

Referring to the drawing, the article holder 1 comprises a base 3, which latter as illustrated is in the form of an angle bracket preferably made of sheet metal. As shown, 25 the flange 5 of this bracket is provided with perforations 7 for receiving screws or the like for attaching it to a support such as, for example, the wall 9 of a cabinet, closet, room, or other structure. Herein, the base 3 of the 30 article holder carries a pair of arms 11, pivotally secured at 13 to the flange 15 of said base. Conveniently, these arms each comprise the similar halves 17 placed at opposite sides respectively of the flange 15 in 35 contacting relation therewith, so that the arms are securely supported for swinging movement in the plane of said flange.

As shown, the arms 11 at their outer ends 40 carry rollers 19, which preferably are formed of rubber or other comparatively resilient material inoperative to scratch or cut or otherwise mar the article, such as the broom handle H, engaged by said rollers. Preferably, the halves 17 of the arms are provided with portions 21 affording large areas of contact with the opposite sides of the rollers so as to hold the latter against flexure. Conveniently, these portions 21 of the arms are offset from the body of the arms so that 45 the latter do not strike the handle H when

the latter is inserted between the arms as shown in Fig. 4.

For urging the arms toward each other, the present embodiment of the invention includes a tension spring 23, which, at opposite ends, has hooked portions 25 extending between the halves 17 of the respective arms and secured to the latter by engagement with pins 27 carried at opposite ends thereof by said halves. Herein, the spring 23 is covered by a flexible tube 29 formed preferably of rubber. As shown, for normally holding the rollers 19 in spaced relation, under the force of the spring urging them toward each other, the flange 15 of the base 3 of the holder is slotted near each of its outer end portions as indicated at 31, the part between said slots being bent downward, as indicated at 33, to form stops for the arms.

The normal position of the holder parts 70 is shown by Fig. 1. By presenting the handle H of a broom or the like to the rollers, and pressing it thereagainst, the arms 11 will be spread apart to permit said handle to pass between them while the handle remains in contact with the rollers, the latter, due to their rotary movement about their pivots, readily permitting this operation and causing the handle to snap into the space between the arms due to the fact that the latter urge said rollers toward each other. The 75 spring means, which herein comprises the spring 23 and its cover 29, is so positioned that it is engaged by said handle, and is bent and stretched by the latter when engaged thereby. The spring means thus acts resiliently to urge the handle against the rollers, and, because it is bent by the handle, acts 80 to increase the force by which said arms press the rollers against the handle.

The above described construction is such 85 that the handle may be readily rotated relative to the holder and without marring the surface of the handle. This is of particular importance where the holder is used for supporting brooms, because commonly the broom will not be presented to the holder with the plane of the broom head B parallel to the wall which supports the holder, resulting, as the 90 broom is inserted, in one side of it striking 95

the wall. Also when a row of holders is provided for supporting a plurality of brooms, it may be necessary, if the holders are placed close together, to rotate the brooms to hold their heads B at an angle to the wall to prevent each broom from contacting or interfering with the adjacent broom.

It will be understood that wide deviations may be made from the present embodiment 10 of the invention without departing from the spirit thereof.

I claim:

1. A holder for articles of the character described having, in combination, a base, a pair 15 of rollers, spaced arms for supporting said rollers, said arms being carried by said base for swinging movement toward and away from each other, and spring means acting on said arms to urge them toward each other, 20 said spring means being so formed and positioned as to engage an article received between said arms for urging said article toward said rollers.

2. A holder for articles of the character 25 described having, in combination, a base, a pair of rollers spaced arms for supporting said rollers, said arms being carried by said base for swinging movement toward and away from each other, spring means acting 30 on said arms to urge them toward each other, said spring means being so formed and positioned as to engage an article received between said arms for urging said article toward said rollers, and stop means for cooperating with said arms for normally holding said rollers in spaced relation.

3. A holder for articles of the character 40 described having, in combination, a base, a pair of article engaging rollers, means carrying said rollers for movement toward and away from each other comprising a pair of relatively movable roller supports carried by said base, a tension spring means connected at opposite ends thereof to said roller supports for urging them resiliently toward each other, said spring means being so formed and positioned as to engage with the article engaged by said rollers for urging said article resiliently toward said rollers.

4. A holder for articles of the character 45 described having, in combination, a base, a pair of article engaging rollers, means carrying said rollers for movement toward and away from each other comprising a pair of relatively movable roller supports carried by said base, a tension spring connected at opposite ends thereof to said roller supports for urging them resiliently toward each other, said spring carrying a part so formed and positioned as to engage with the article engaged by said rollers for urging said article toward said rollers.

5. A holder for articles of the character 55 described having, in combination, a base having a relatively thin arm supporting portion, a

pair of arms, said arms each comprising parallel portions pivoted to said arm supporting portion at opposite sides of the latter respectively, said arms at their free ends being offset toward each other, rollers of comparatively resilient material pivotally carried by the offset portions of said arms, spring means connected at opposite ends thereof to said arms and bridging the space between them for urging said arms toward each other and for engaging the article and urging it toward said rollers, and stop means formed integrally with said base acting on said arms for normally holding said rollers out of contact with each other.

6. A holder for articles of the character described having, in combination, a pair of articles engaging members, means for supporting said members for movement toward and away from each other, means acting resiliently to urge said members toward each other, the last mentioned means having a portion so formed and positioned as to engage an article placed between said members for urging the article into contact with said members.

7. A holder for articles of the character described having, in combination, a base, means comprising a pair of arms mounted on said base for swinging movement and having parts at the ends of said arms for engaging an article placed between them, a tension spring means connected at opposite ends to said arms, said spring means being so formed and positioned as to be engaged by an article placed between said arms and to be tensioned by said article.

In testimony whereof, I have signed my name to this specification.
